United States Patent Office

Des. 202,819
Patented Nov. 9, 1965

202,819

PULPING UNIT

Sam N. Craig, Devon, Pa., assignor to Somat Corporation, Coatesville, Pa., a corporation of Delaware

Filed Mar. 24, 1965, Ser. No. 84,419

Term of patent 14 years

(Cl. D55—1)

FIG.1

FIG.2

FIG.3

FIG.6

FIG. 4

FIG. 5

FIG. 1 is an elevation of one side of a pulping unit showing my new design;

FIG. 2 is a top plan view thereof;

FIG. 3 is an elevation of the remaining side;

FIG. 4 is an elevation of one end thereof;

FIG. 5 is an elevation of the remaining end; and

FIG. 6 is a vertical transverse cross-sectional view thereof taken on the line 6—6 in the direction of the arrows as shown in FIG. 1.

I claim:

The ornamental design for a pulping unit, substantially as shown.
